UNITED STATES PATENT OFFICE.

ALFONZ H. MEYER, OF YAKIMA, WASHINGTON.

EXTENSION LADDER.

Application filed November 10, 1925, Serial No. 69,173.

My present invention pertains to extension ladders, and one of its objects is the provision of a holder for extension ladders capable of being expeditiously and easily accommodated to uneven ground.

Other objects and practical advantages of the invention will be fully understood from the following description and claim when the same is read in connection with the drawings, accompanying and forming part of this specification, in which:

Figure 1 is a front elevation of the ladder constituting the preferred embodiment of my invention, the ladder being shown in said figure with the prop member omitted.

Figure 2 is a complete view of the ladder shown in edge elevation, with a portion broken away.

Figure 3 is an enlarged inverted fragmentary view showing a portion of one of the steps of the upper section.

Figure 4 is an inverted plan view on an enlarged scale showing the next to the upper step of the lower ladder section and also showing the appurtenances thereof for adjustably locking the ladder sections together.

Figure 5 is a fragmentary inverted plan view showing a portion of the lower step of the ladder, which step is comprised in the holder hereinafter described, and also illustrating the appurtenances of said step.

Figure 6 is a view showing in rear elevation the complete ladder.

Figures 7, 8 and 9 are enlarged horizontal sections taken in the planes indicated by the lines 7—7, 8—8 and 9—9, respectively, of Figure 1, and hereinafter explicitly referred to.

Figure 10 is a detail cross section through one of the steps and illustrating the manner in which the latch bolts are held in place.

Figure 11 is an enlarged detail section illustrative of the dog 47 and the parts adjacent thereto.

Similar numerals of reference designate corresponding parts in all of the views of the drawings.

The holder hereinbefore alluded to is shown in Figures 1, 5 and 6, and among other elements the said holder includes a horizontal body bar 1, provided at its underside with a longitudinal central strengthening rib 2 and having at its ends appropriate guides 3 for holding therein spring-pressed latch bolts 4 on which are finger pieces 5 which extend upwardly from the latch bolts

4 as will be readily understood from Figure 1. The springs backing the bolts 4 are designated by 6. The bar 1 is adapted to constitute the lowest step of the structure, Figure 1, and it will be understood that the side stiles 7 of the lower ladder section are superposed on and appropriately connected to the said body bar 1. The holder also comprises an upper transverse bar 8, fixedly connected at 9 to the said side stiles 7, inclined sleeve or tubular portions 10 of any suitable cross-section interposed between and connected to the body bar 1 and the cross bar 8 and fixed thereto, and legs 11 sheathed in the said sleeves or tubular portions 10 and having at intervals in their lengths apertures 12 to receive the before mentioned latch bolts 4. By virtue of this construction of holder, the ladder as a whole may obviously be readily accommodated to uneven ground and to inclinations.

At 13 the lower section of the ladder is provided with a hand hold and rung to facilitate the handling of the structure.

The side stiles 14 of the upper ladder section are spaced a greater distance apart than the side stiles 7 of the lower section and are designed to rest longitudinally at the outer sides of the said stiles 7 and be capable of longitudinal movement thereon. At 15 and 16 the lower section is provided with steps interposed between the side stiles 7 and fixed thereto in any appropriate manner. At their upper ends the side stiles 14 are connected by a crown bar 17, and immediately below the said crown bar 17, crossed braces 18 are interposed between and fixed to the side stiles 14. As illustrated the upper section of the ladder comprises four steps 19, one of the said steps 19 being shown in detail in Figure 3. It will also be noticed that the side stiles 14 of the upper section are provided with openings 20, which are preferably, though not necessarily, of the configuration shown in Figure 2. Each of the steps 19 is provided at its ends with spring-pressed bolts 22, designed to be seated in two of the apertures 20 with a view to strongly and safely supporting the steps on the side stiles 14. The bolts 22 may be moved inwardly by pressure applied to their outer ends or in any other approved manner. Each of the steps 19 is also provided with hooks 23, spaced from the ends of the steps and carried by bars 24 of metal, opposed to the front edge of the step and

fixedly connected to the step by lugs 25 and screws 26 extended through said lugs and into the step, it being understood in this connection that each of the steps 19 is preferably formed of wood. By virtue of the specific construction just described it will be manifest that each of the steps 19 will be strongly held to and supported by the side stiles 14, and that the steps 19 will operate to strongly hold the stiles 14 together and against outward movement.

Carried adjacent to the upper ends of the side stiles 7 of the lower ladder section is a step member 30, appropriately connected to the side stiles 7 and having at its ends guide loops 31 arranged to receive the side stiles 14 of the upper section. Spaced below the member 30 is a member 32 with end loops 33 which receive the side stiles 7 and 14 with a view to holding and guiding the side stiles 14 so that the side stiles 14 will be held against lateral deflection relative to the side stiles 7. The member 32 is shown in detail in Figure 4 and in Figure 8, as well as in Figure 1, and by comparison of the said figures the member 32 will be understood as having latch bolts 34, equipped with pendent finger pieces 35 and pressed outwardly by spring means 36, this in order that the said latch bolts 34 will tend to enter and remain against casual displacement in apertures 20 in the side stiles 14, it being understood in this connection that the bolts 34 are passed through openings in the side stiles 7 precedent to entering the said apertures 20.

It will be apparent from the foregoing that when the bolts 34 are retracted, the upper section of the ladder may be expeditiously and easily raised or lowered on the lower section; and it will also be apparent that when for any reason it is desired to disconnect one of the step members 19 from the side stiles 14 the disconnection may be readily effected.

In addition to the elements named, my novel ladder comprises a prop member which is so arranged that it will not interfere with the arrangement of the ladder in inclined position against a wall or other upright support, and yet may be quickly and easily positioned so as to constitute the sole support of the ladder. The said prop member is made up of a sleeve 40 and a bar 41 telescopically arranged in the sleeve 40. The said sleeve 40 and bar 41 are disposed in the longitudinal center of the ladder structure, and the sleeve 40 is provided at its upper end with a T-head 42, pivotally connected at 43 to flanges 44 on the crown bar 17 and connected with an intermediate portion of the sleeve 40 through the me-

dium of metallic braces 45. The bar 41 is provided at intervals in its length with notches 46, the upper walls of which are inclined as shown in Figure 2. For use in conjunction with the said notches 46 the sleeve 40 is provided with a spring dog 47, having a finger piece as illustrated and therefore adapted to be drawn out of engagement with the particular notch 46 that is opposed to it, it being understood here that the normal tendency of the latch 47 is to spring into the notches 46 of the bar 41 so that when the bar 41 is drawn downwardly in the sleeve 40 the latch 47 will permit of said movement and yet will preclude accidental movement of the bar 41 in the opposite direction when the latch 47 is seated in the particular notch 46 that it is necessary to use for the correct positioning of the bar 41, to support the ladder structure at the point desired. Manifestly when the bar 41 is moved downwardly in the sleeve 40, the upper inclined walls of the notches 46 will ride over and press outwardly the dog 47.

It will be readily manifest from the foregoing that the prop member of my improvement may be increased and diminished in length as the upper section of the ladder is adjusted with respect to the lower section thereof.

I have specifically described the construction and relative arrangement of the parts embraced in the present and preferred embodiment of my invention in order to impart a full, clear and exact understanding of the said embodiment. I do not desire, however, to be understood as confining myself to the construction and arrangement disclosed, my invention being defined by my appended claim within the scope of which changes in the structure and in arrangement may be made without departure from my invention.

Having described my invention, what I claim and desire to secure by Letters Patent, is:-

In a ladder structure, a ladder having side stiles and steps between the same, in combination with a holder made up of a body bar upon which the side stiles are superposed, a top portion spaced above said body bar and connected to the side stiles, inwardly inclined sleeves interposed between and fixed to the ends of said body bar and top portion, apertured legs telescopically arranged in said sleeves, and latch bolts carried by the body bar and adapted to seat in the apertured legs to retain the latter in different adjusted positions.

In testimony whereof I affix my signature.

ALFONZ H. MEYER.
